FLUORESCENT LAMP HEAD

James F. Sullivan, Eastchester, N.Y., assignor to Kulka
Electric Corp., Mount Vernon, N.Y.

Filed Mar. 16, 1972, Ser. No. 235,465

Term of patent 14 years

Int. Cl. D26—04

U.S. Cl. D26—8

FIG. 1

FIG. 2

FIG. 3

FIG. 5

FIG. 4

FIG. 1 is a perspective view of a fluorescent lamp head showing my new design;

FIG. 2 is a top plan view thereof;

FIG. 3 is a side elevational view thereof;

FIG. 4 is an end elevational view thereof; and

FIG. 5 is a bottom plan view thereof.

I claim:

The ornamental design for a fluorescent lamp head, substantially as shown.
